UNITED STATES PATENT OFFICE.

GEORGE M. HUBBARD, OF NEW HAVEN, CONNECTICUT.

DESIGN FOR A BELT-CLASP.

SPECIFICATION forming part of Design No. 19,860, dated May 27, 1890.

Application filed April 24, 1890. Serial No. 349,377. Term of patent 7 years.

To all whom it may concern:

Be it known that I, GEORGE M. HUBBARD, of New Haven, in the county of New Haven and State of Connecticut, have invented a new 5 Design for Waist-Belt Clasps; and I do hereby declare the following, when taken in connection with accompanying drawing and the letters of reference marked thereon, to be a full, clear, and exact description of the same, 10 and which said drawing constitutes part of this specification, and represents a face view of the same.

This invention relates to a design for belt-clasps; and the design consists in the configuration and ornamentation of the parts, as 15 hereinafter described, and shown in the accompanying illustration.

A represents one loop, and B the other loop. Projecting from one side of the loop A is the representation of a buckle C, and from the corresponding side of the other loop B is the representation of a leather strap D.

The parts combined, as shown, represent a buckle and strap as connecting the two loops.

I claim—

The design for a belt-clasp, as herein shown and described.
